CHILDREN'S GAME BOARD

Rose Daves, Franklin Square, N. Y.

Application November 9, 1954, Serial No. 33,044

Term of patent 14 years

(Cl. D25—1)

The single figure is a top plan view of a children's game board, showing my new design.

The game board is of no appreciable thickness, and the back thereof, not shown, is plain or conventional.

The broken line showing of legible matter is for illustrative purposes only.

I claim:

I claim:
The ornamental design for a children's game board, as shown and described.
